UNITED STATES PATENT OFFICE.

FRANK PASTOR, OF AKRON, OHIO, ASSIGNOR OF ONE-HALF TO FRANK CSEMA, OF AKRON, OHIO.

RAIL-JOINT.

1,114,027.

Specification of Letters Patent.

Patented Oct. 20, 1914.

Application filed July 28, 1914. Serial No. 853,587.

To all whom it may concern:

Be it known that I, FRANK PASTOR, a subject of the Emperor of Austria-Hungary, residing at Akron, in the county of Summit 5 and State of Ohio, have invented certain new and useful Improvements in Rail-Joints, of which the following is a specification.

This invention relates to new and useful 10 improvements in rail joints.

The primary object of the invention is to provide a jointure for contiguous rail ends which will securely lock the rails together in longitudinal alinement and without the 15 use of bolts or nuts and at the same time forming a union that may be readily separated if found desirable.

A further object is to provide the opposite rail ends of substantially complementary 20 formation and whereby the ends of contiguous rails will readily interlock when brought into abutting alinement with each other.

A still further object is to provide rail 25 ends of such forms as to be interengageable upon proper positioning followed by a partial revolution of either one of the rails and forming a secure connection when the rails are in alinement with each other and in their positions for use.

With these general objects in view and others that will appear as the nature of the 30 invention is better understood, the same consists in the novel combination and arrangement of parts hereinafter fully described, 35 illustrated in the accompanying drawings and pointed out in the appended claims.

In the drawings forming a part of this 40 application and in which like designating characters refer to corresponding parts throughout the several views:—Figure 1 is a horizontal central sectional view taken through the interlocked ends of two rails, a portion of one of said rails being shown in top plan view. Fig. 2 is a side elevation of 45 the interlocked end portions of two rails, one of the same being partially shown in central vertical section. Fig. 3 is a view similar to Fig. 1 but showing one of the rails as partially revolved in the operation 50 of effecting the locking engagement. Fig. 4 is a vertical transverse sectional view taken upon line IV—IV of Fig. 2. Fig. 5 is a similar view taken upon line V—V of Fig. 2. and Fig. 6 is a perspective view of the end 55 portion of one of the rails.

Referring more in detail to the drawing, it will be noted that the invention is designed to provide a rigid connection between two railroad rails such as 10 and 11 being of identical form and adapted to be 60 positioned in longitudinal alinement in making up one of the continuous rails of a railroad track.

One of the rails as 10 is provided with a central longitudinal bore or socket 12 open 65 at the end of the rail and provided with a central contracted portion 13 which forms an elliptical opening 14 between the outer portion 15 and the inner portion 16 of the said socket.

The rail 11 is provided with a centrally projecting longitudinally positioned spindle 17 at the end thereof having its base portion 18 adjacent the end face 19 of said rail 11 of cylindrical form and provided with a reduced cylindrical extension 20 terminating in an outwardly positioned flattened head 21.

The manner of connecting and disconnecting the rails by means of this joint will 80 be at once apparent from the above detailed description, it being only necessary to enter the spindle 17 into the socket 12 and turning the spindle carrying rail end sufficiently to allow the flattened head 21 to pass through 85 the elliptical opening 14 as illustrated in Fig. 3 and to such a position as to place said head within the socket portion 16, whereupon a further turning of the rail 11 to its normal operative position places the head 90 21 transversely behind the opening 14 so that the engagement of the head with the contracted portions 13 prevents a withdrawal of the head and the spindle. It will also be seen that the rails may be disconnected by turning one of the rails sufficiently to allow the head 21 to be withdrawn through the opening 14 and whereupon the rails may be readily separated. When the 95 members are in their assembled and locked 100 relations, the opposite sides of the contracted portions 13 will be engaged by the inner faces 22 of the head 21 and by the outer annular face 23 of the cylindrical spindle portion 18. It will also be noted that the 105 socket portion 16 has an opening 24 at the bottom thereof for the prevention of a filling of the socket by dirt or foreign matter.

While the forms of the invention herein shown and described are what are believed 110

to be preferable embodiments thereof, it is nevertheless to be understood that minor changes may be made in the form, proportion and details of construction without departing from the spirit and scope of the invention as set forth in the appended claims.

What I claim as new is:—

1. A rail joint comprising complementally formed rail ends, one of said ends provided with a central longitudinal bore opening at the end of the rail and having the sides of said bore at a point substantially centrally thereof contracted to form an elliptical slot, the other of said rail ends having a centrally longitudinally projecting spindle formed with a central contracted portion and a terminal flattened head, the head of said spindle adapted for passing through said elliptical slot during the assembling or disassembling operation.
2. A device of the class described comprising a rail end having a central longitudi-

dinal socket opening at the end of the rail and having the inner end of the socket opening at the bottom of the rail, inwardly positioned portions of the rail intersecting said bore and forming an elliptical passage between the opposite end portions of said socket at the opposite sides of said inwardly positioned portions, a second rail end, a longitudinally positioned centrally projecting cylindrical spindle thereon having a terminal flattened head and an intermediate contracted cylindrical connecting portion, the said spindle adapted for seating within said socket upon a passing of said head through said elliptical opening.

In testimony whereof I affix my signature in presence of two witnesses.

FRANK PASTOR.
